(57) **CLAIM**

The ornamental design for a lite, as shown and described.

DESCRIPTION

FIG. 1 is a front perspective view of a first embodiment of my lite;

FIG. 2 is a front elevational view of the lite of FIG. 1, with the rear being a mirror image thereof;

FIG. 3 is a front perspective view of a variation thereof; FIG. 4 is a front elevational view of the lite of FIG. 3, with the rear being a mirror image thereof;

FIG. 5 is a front perspective view of a second embodiment of my lite;

FIG. 6 is a front elevational view of the lite of FIG. 5, with the rear being a mirror image thereof;

FIG. 7 is a front perspective view of a variation thereof; and, FIG. 8 is a front elevational view of the lite of FIG. 7, with the rear being a mirror image thereof.
